UNITED STATES PATENT OFFICE

HEINRICH BERTSCH, OF CHEMNITZ, GERMANY, ASSIGNOR TO H. TH. BÖHME AKTIEN-
GESELLSCHAFT, OF CHEMNITZ, GERMANY, A CORPORATION OF GERMANY

WETTING AGENTS

No Drawing. Application filed July 29, 1929, Serial No. 382,077, and in Germany September 5, 1928.

The fatty acids, particularly unsaturated and hydroxy fatty acids, are used in various forms for a multiplicity of purposes in industry, more especially in the textile and leather industries. The forms in which they are most frequently used are their salts, the soaps, and the salts of their sulphuric esters, the Turkey red oils. Both classes of substances, in spite of all other differences, exhibit a common defect, namely that they form insoluble salts, the so-called lime soaps, with alkali earth and metal salts contained in water with which they are used. This is to be ascribed to the fact that the soaps and Turkey red oils contain carboxyl groups still capable of reaction. Recently products similar to Turkey red oils but having a high content of organically combined sulphuric acid and thus a relatively high resistance to lime have been produced successfully by using special methods of sulphonation. The formation of lime soaps can be entirely obviated, however, only by complete elimination of the carboxyl group which is capable of reaction. This is possible, for instance, by sulphonating the alcohols corresponding to the higher fatty acids instead of the fatty acids themselves. By the sulphonation of the former, products are obtained which are extraordinarily insensitive to lime and magnesia salts.

The object of the present invention is to provide a further class of products or preparations which may be added to treatment agents instead of soaps. Turkey red oils or the like. This class comprises the sulphuric esters of the amides, anilides or other amides substituted in the ammonia radicle of fatty or oily acids of high molecular weight. These products may be obtained in various ways, for example by sulphonating the amides, anilides and so forth of higher fatty acids, particularly the amides and anilides of unsaturated or hydroxy-fatty acids. Thus for instance, the oleic acid amide produced in known manner may be treated with the usual sulphonating agents such as concentrated sulphuric acid, fuming sulphuric acid or chloro-sulphonic acid, if occasion demand in the presence of water binding agents such as

anhydrous organic acids, their anhydrides or chlorides. In this manner the sulphuric esters of the fatty acid amides, anilides and so forth are obtained more or less according to the following scheme:

The neutralized sulphonation products, apart from their powers of resistance which in this case also are dependent upon the absence of any free carboxyl group, exhibit high wetting, foaming, emulsifying and cleaning properties and also the characteristic of imparting a soft, smooth, but not sticky feel to textile fibres and allied materials. Said products are, therefore, suitable for manifold uses in the textile and leather industries and also for other purposes.

Thus in all forms of treatment of textiles with neutral, acid or alkali treatment liquids, said products enhance the action by the materially increased wetting and impregnation achieved and by the conversion of fats, impurities and the like into aqueous dispersions.

In vat dyeing the addition of such products enables the reduction to be performed in the presence of little, or weak, alkali, which is important in the dyeing of vat dyestuffs on animal fibres. In naphthol red dyeing it is in this manner possible to dye even on animal fibres if desired. Addition of the substances above referred to also facilitates the moistening or wetting of pulverulent dyestuffs and other powders for their conversion into aqueous liquids, for the production of pastes and so forth. For spinning purposes, their aqueous dispersions with or without further additions have proved to be valuable moistening agents. Similarly the action of treatment liquids in the manufacture and handling of leather is accelerated, strengthened and advantageously modified by the addition of the sulphonated fatty acid amides.

Said compounds are also capable of being used with advantage in the paper manufacturing and treating industry, in the manufacture of pigment colors, in the dyeing of

- furs, wherever it is a question of the wetting effect, dispersion, penetration and conveyances of effective substances or components. The properties of said products also allow of their use in pharmacy as emulsifiers, in the pharmaceutical industry as foaming agents and skin-protective media and also as constituents of salves and creams, as a substitute for vasenols and the like.
- 10 It is a characteristic feature of said products that they render textile fibres and other materials treated therewith soft and pliable without giving the same a sticky feel so that they are suitable for the softening or reviving of such materials.

Their efficacy as agents in the extermination of pests depends upon the same powers of active wetting and penetration. The products are also valuable as additions to corrosives and as boring oils in the metal industry. Furthermore they may be employed as dispersives of the nature of protective colloids, for instance, in the manufacture of ink and in fat cleavage. Their penetrating powers are of advantage when they are used as additions to ceramic masses and their rapidly effective wetting powers make them useful as dust-binding agents.

In the appended claims, the expression "increasing the penetrating power" is employed to describe that power of reagents to come easily or quickly into contact with the material being treated, whether it be in a wetting, dispersing, impregnating, foaming, emulsifying, cleaning or a like process. Further, the term "fatty acid" in the absence of limiting modifiers is employed in its broad sense and also refers to, in addition to the acids of the fatty acid series, other oily acids, including the unsaturated and the hydroxy acids.

I claim:—

1. A reagent for increasing the penetrating power of treating agents comprising, a sulphuric acid ester of an amide of a higher fatty acid.
2. A reagent adapted for increasing the penetrating power of treating agents used in the textile, leather, paper and fat-con-

50

verting industries and the like, comprising a sulphuric acid ester of an anilide having substituted for hydrogen in its nitrogen nucleus an acyl radical derived from a higher fatty acid.

70 3. A composition of matter for treating fibrous pulverulent and water-repellent materials, and materials not readily soluble comprising a sulphuric acid ester of an amide of a higher fatty acid in combination with a known agent adapted for altering the properties of such materials, said composition having increased efficiency including penetrating power over the known agent when used alone.

75 4. In the process of producing a wetting, foaming or dispersion agent adapted for the treatment of fibrous, pulverulent, water-repellent materials, and difficultly soluble materials, the step comprising incorporating in said agent sulphuric acid esters of amides of the higher fatty acids.

80 5. A composition of matter comprising a treating agent dependent in part for its effectiveness upon its penetrating power into such materials as fibrous, pulverulent, water-repellent materials and difficultly soluble materials, in combination with a substance adapted to enhance the penetrating power of said agent consisting in a sulphuric acid ester of an amide of an acid of the higher fatty acid series.

85 6. A reagent for enhancing the wetting, impregnating, foaming, emulsifying, dispersing, cleaning and like properties of treating agents comprising a sulphuric acid ester of an amide of a higher saturated fatty acid.

90 7. A reagent for enhancing the wetting, impregnating, foaming, emulsifying, dispersing, cleaning and like properties of treating agents comprising a sulphuric acid ester of an amide of a higher unsaturated fatty acid.

95 8. A reagent for enhancing the wetting, impregnating, foaming, emulsifying, dispersing, cleaning and like properties of treating agents comprising a sulphuric acid ester of an amide of a higher hydroxy fatty acid.
